UNITED STATES PATENT OFFICE

98,168

DESIGN FOR A SADIROH HANDLE SUPPORT

Ivar Jepson, Chicago, Ill., assignor to Chicago
Flexible Shaft Company, Chicago, Ill., a cor-
poration of Illinois

Application September 30, 1935, Serial No. 58,767

Term of patent 7 years

To all whom it may concern:

Be it known that I, Ivar Jepson, a citizen of the United States, residing at Chicago, in the county of Cook and State of Illinois, have invented a new, original, and ornamental Design for a Sadiron Handle Support, of which the following is a specification, reference being had to the accompanying drawing, forming part thereof.

The dominant feature of the design resides in the portions shown in full lines.

In the drawing:

Figure 1 is a side perspective view of a sadiron handle support showing my design;

Fig. 2 is a side view thereof;

Fig. 3 is a front view thereof;

Fig. 4 is a section on the line 4—4 of Fig. 2 showing the shape characteristics of the upper portion of the support, and

Fig. 5 is a section on the line 5—5 of Fig. 2 showing the shape characteristics of the lower portion of the support.

I claim:

The ornamental design for a sadiron handle support substantially as shown and described.

IVAR JEPSON.
